UNITED STATES PATENT OFFICE.

EDGAR F. HATHAWAY, OF DORCHESTER, MASSACHUSETTS, ASSIGNOR TO MOHAWK CARPET MILLS, INC., OF AMSTERDAM, NEW YORK, A CORPORATION OF NEW YORK.

STOPPING MECHANISM FOR TEXTILE MACHINERY.

1,419,731.

Specification of Letters Patent. Patented June 13, 1922.

Application filed March 5, 1921. Serial No. 449,889.

To all whom it may concern:

Be it known that I, EDGAR F. HATHAWAY, a citizen of the United States, and a resident of Dorchester, in the county of Suffolk and State of Massachusetts, have invented an Improvement in Stopping Mechanism for Textile Machinery, of which the following description, in connection with the accompanying drawings, is a specification, 10 like characters on the drawings representing like parts.

This invention relates to stopping mechanism for textile machinery and particularly to weft stopping mechanism, and more 15 particularly to weft stopping mechanism for chenille forming mechanism wherein separate weft lengths are laid in the shed as disclosed in my application Serial No. 449,887.

20 In order that the principle of the invention may be readily understood, I have disclosed a single embodiment thereof in the accompanying drawings, wherein—

Fig. 1 is a view partially in side elevation and partially in vertical section of a stop motion embodying my invention;

Fig. 2 is a detail representing the lower part of the mechanism shown in Fig. 1 but with a different position of parts;

30 Fig. 3 is a view in side elevation of the upper part of the mechanism shown in Fig. 1 and indicating also the weft presenting device and the weft carrier or weft laying device;

35 Fig. 4 is a detail in side elevation of the upper part of the mechanism shown in Fig. 1 and indicating, upon an enlarged scale, in full and in dotted lines, two positions of the parts;

40 Fig. 4^a is a detail in elevation of a part of the construction shown in Fig. 4;

Fig. 5 represents the clutch shaft and connections thereto for positioning the parts for high speed, for low speed and for neutral position; and

Fig. 6 is a view in side elevation and vertical section representing the brake means preferably employed.

In my co-pending applications Serial Nos. 449,887 and 449,888, I have disclosed means for forming chenille and including means for presenting the weft thread or threads selectively to be grasped by a suitable weft carrier. Herein I have indicated at 1 in 55 Fig. 3 one of the weft tubes or fingers by

which yarn is selectively presented to be grasped by the jaws 2 of the weft carrier 3. Preferably also and as shown in certain of said applications weft severing means are employed to sever the weft as laid at each 60 end of the shed.

The subject-matter of the present application relates more particularly to means for stopping the operation of the mechanism in case the weft thread fails of presentation or other like weft fault. I have indicated diagrammatically the warps forming the shed at 4, 5 in Fig. 1 and take-up rolls 6, 7, over which the woven fabric 8 passes. The weft itself is indicated at 9 in 70 Figs. 1 and 3. At a suitable point between the end 10 of the weft presenting finger 1 and the weft seizing position of the weft carrier 3, I provide a feeler 11 preferably formed as a finger upstanding from a rock 75 shaft 12 which is mounted in guides in uprights 13, 13 upon the top of the lay 14, all as indicated in Fig. 3.

Fast upon the rock shaft 12 is a second finger 15 and also fast thereon is a depending lever arm 16 having a hook 17 at its lower end. In a manner to be hereinafter described, the rock shaft 12 is caused to rock so that the finger 11 feels for the weft 9. If the latter be present the finger 11 is 80 limited in its movement thereby, but if the weft be absent, then the finger 11 moves into the dotted line position shown in Fig. 4, thereby causing the finger 15 and the lever arm 16 to move into their dotted line positions, also shown in Fig. 4, and thereby to 85 stop the operation of the mechanism in a manner which will be hereinafter described.

Upon a suitable shaft 18 is fast a cam 19 having a projection 20, said cam rotating 95 once to each beat-up of the lay. Bearing upon the periphery of the cam 19 is a roll 21 carried by the arm 22 of a lever pivoted at 23; the opposite arm 24 of said lever having pivoted at its outer end at 25 a bell 100 crank lever provided with arms 26, 27. Tapped into the free end of the arm 26 is a threaded bolt or screw 28, the lower end of which is adapted to take against a stop or projection 29 upon the face of the lever 105 arm 24. A coil spring 30 is attached at one end to the lever arm 26 and at its other end to the lever arm 24, so as yieldingly to hold the lower end of the bolt or screw 28 against the stop 29. The lever arm 26 is provided 110

with a hole or opening through which freely passes the lower end of a long rod 31 here shown as bent in its lower portion. Any suitable form of rod may, however, obviously be provided.

Said rod 31 is guided at its upper end in a bracket 32 formed, if desired, with the uprights 13, 13 upon the lay 14. Mounted for vertical sliding movement in the guide 32 is a short upright rod 33 which at its upper end has a laterally extending head 34 adapted to be engaged by the finger 15 in the swinging movement of the latter and to be depressed if the finger 15 moves into its dotted line position indicated in Fig. 4. At its lower end the rod 33 has secured thereto a transversely extending foot or member 35 provided with a laterally extending projection 36 indicated most clearly in Fig. 4^a.

When the lever arm 16 with its hook 17 is moved as described in the dotted line position shown in Fig. 4, it intercepts or comes into the path of downward movement of the projection 36 of the member 35. The member 35 is fast upon the upright rod 31 and the engagement of the projection 36 thereon with the hook 17 prevents the full downward normal movement of the rod 31 due to the action of the cam 19, 20.

In the normal operation of the parts the rod 31 is constantly reciprocated vertically from the cam 19, 20, and the small bell crank lever 26, 27 has no rocking movement or movement relative to the swinging movement of the lever 22, 24. In such normal operation of the parts, the arm 27 of the small bell crank lever in its lower position assumes the dotted line position shown in Fig. 1 and the operation of the mechanism continues. If, however, the downward movement of the rod 31 be interrupted, then in the downward movement of the lever arm 24, the coiled spring 37, which encircles the lower end of the rod 31 between the lever arm 26 and the fixed collar 38, is compressed and offers sufficient resistance to prevent the normal swinging of the bell crank 26, 27. The result is that the lower end 39 of the lever arm 27 engages the shoulder 40 of the lever arm 41 of a lever pivoted at 42. The opposite arm 43 of said lever is provided with a projection 44 furnishing a shoulder 45. The lever 41, 43 is normally held in the position shown in Fig. 1 by a coiled spring 46 connected at one end at 47 to the lever arm 41 and at its other end at 48 to a projection upon the large bell crank lever 22, 24.

In a suitable bracket 49 shown most clearly in Fig. 5, there is mounted a rock shaft 50 having at one end a bevel pinion 51 meshing with a similar pinion 52 upon the clutch shaft 53 hereinafter more fully referred to. Loose upon said shaft 50 and as best shown in Fig. 1 is a lever arm 54 which

at its upper end has a T or hammer head providing shoulders 55, 56. The lever arm 54 is provided with a laterally extending portion 57 upon which are ribs 58, 59 spaced apart a greater distance than the width of the arm 60 of a segment-like member 61 fast upon the shaft 50. Said member 61 is provided with a second arm 62 joining which is a web 63 terminating at one end in the inclined shoulder 64 and at the other end at the shoulder 65. Thus a lateral projection 66 upon the lower end of the lever arm 41 is adapted to ride along the shoulder 64, the concentric edge 67 of the rib 63 and the shoulder 65, for a purpose hereinafter more fully stated.

Pivotedly connected at 68 to the lever arm 54 is a rod 69 which is guided for sliding movement in a fixed post or part 70 upon a suitable part of the framing. The said rod 69 has fast thereon two collars 71, 72 between which and the said post 70 are provided two coil springs 73, 74. Tension of the said two springs is equalized when the mechanism is in neutral position, that is, when the mechanism is stopped upon the breaking of a thread and as indicated in Fig. 2. When, however, the mechanism is running at high speed which is the position of the parts indicated in Fig. 1, the spring 73 is under the greater compression and tends to move the rod 69 to the right viewing Fig. 1.

Assuming the absence of the weft 9 at the proper time, it will be evident that the finger 11 will descend into the dotted line position indicated in Fig. 4, and thereupon the downward movement of the rod 31 will be stopped. Consequently the lever arm 27 will engage the shoulder 40 of the lever arm 41 and will rock said lever 41, 43 so that the lateral projection 66 rides upon the shoulder 64 onto the concentric face 67 of the rib 63. This will withdraw the notch 45 of the lever arm 43 from the shoulder 55 of the lever arm 54 and consequently the latter is free to be moved in a clockwise direction, viewing Fig. 1, under the stress of the spring 74. Such movement of the lever arm 54 causes like movement of the segment-like member 61 through engagement of the rib 59 with the edge of the lever arm 60, there being as indicated a certain amount of lost motion or play for a purpose hereinafter set forth. The movement of the segment-like member 61 which, as stated, is fast upon the shaft 50, causes rocking movement of the latter, and consequently rocking movement of the clutch shaft 53. Fast upon said shaft 53 are yokes 75, 76 which engage 125 the groove 77 in the clutch member 78, thus throwing the parts into the neutral position indicated in Fig. 2.

Upon the main drive shaft 79 which carries the clutch member 78 are provided two 130

gears 80, 81 which when fast thereon respectively drive the mechanism at low speed and at high speed. Consequently the position of the clutch shaft 53 determines 5 whether the machine shall operate at low speed or at high speed or shall stand still.

When the parts of the mechanism are operating at high speed, the shoulder 55 of the lever 54 is in engagement with the 10 shoulder 45 of the lever arm 43, as indicated in Fig. 1, and the spring 74 is under compression, the spring 73 at such time being substantially neither under expansion nor compression. When the machine is operated 15 at low speed, the shoulder 82 at the opposite face of the projection 44 of the lever arm 43 comes into contact with the shoulder 56 of the lever 54 and at the same time the spring 73 is under compression and the 20 spring 74 is free from compression. When the parts are in the neutral or stopped position, indicated in Fig. 2, both springs 73, 74 are substantially free from compression and equalize each other, as previously stated.

25 I provide means whereby the mechanism may manually be brought into any one of the three positions described. In other words, there is capacity for stopping the machine, either automatically or manually, 30 and for bringing the mechanism manually into either high speed or low speed. Moreover there is capacity to stop the machine whether it be running at high speed or low speed provided there is failure or fault of 35 the weft.

In order to perform said manual operations, I have herein for the purpose provided a lever 83 pivoted at 84 upon the framing and having a handle 85 for manual 40 operation. To a projection 86 of said lever arm there is pivoted at 87 a link 88 which at its opposite end is pivoted at 89 to the arm 60 of the segment-like member 61. When said lever 83 occupies the full line position shown, 45 the mechanism is running at high speed. When it is desired to stop the mechanism manually, the lever 83 is moved in a clockwise direction into the dotted line position indicated in Fig. 1, this being an intermediate position, and it is obvious that the pull through said lever 83 upon the segment-like lever 61 causes the projection 66 of the lever arm 41 to ride up the inclined shoulder 64, thereby releasing the projection 44 from 50 the head of the lever 54. This action is permitted because of the fact that the ribs 58, 59 are spaced apart a greater distance than the width of the lever arm 60, thus permitting initial movement of the segment-like lever 61 before movement of the lever arm 54 is possible. The riding of the projection 66 up the inclined surface 64 and onto the concentric face 67 of the rib 63 causes 55 the swinging of the lever arm 43 in a contraclockwise direction, thus releasing the

lever 54 and permitting said lever to be brought into the neutral position indicated in Fig. 2. In order to bring the parts into the low speed position, the lever arm 83 is swung still further in a clockwise direction 70 to the second position indicated in dotted lines, and thereupon the shoulder 56 of the lever 54 is brought into engagement with the shoulder 82 at the right hand side of the projection 44 of the lever arm 43. 75

Preferably I provide means to apply a brake to the drive shaft 79 when the mechanism is brought into neutral position. For this purpose and as shown most clearly in Figs. 5 and 6, I have keyed upon the shaft 80 79 a drum or disk 90 to which is adapted to be applied a brake shoe 91 pivoted at 92 upon a lever arm 93 itself pivoted at 94 upon the framing. Integral with the lever arm 93 is a lever arm 95 having a split portion to 85 receive an adjusting screw 96, a screw 97 being provided to tighten the split portion with respect to said screw. The lower end of the screw 96 may take against a lateral projection 98 on a lever arm 99, itself also 90 fast with the lever arms, 93, 95. The lever arm 99 is normally pressed in a clockwise direction by a pin or push rod 100, the inner end of which takes into a socket 101 in the lever 93, there being an elongated coil spring 95 102 about said pin or push rod and confined between a collar 103 fast on said rod or pin and the bearing upon the framing, not shown, for said pin.

Upon the shaft 50 for operating the clutch 100 lever is fast a cam lever 104 having therein a notch 105 into which a roll 106 upon the lever arm 99 is adapted to take. When the cam lever 104 is in the position shown in Fig. 6, the clutch is in its neutral position, 105 and the spring 102 is permitted because of the reception of the pin 106 in the notch 105 to force the rod or pin 100 to the left, viewing Fig. 6, and thereby to force the brake 91 against the disk or drum 90. When the 110 mechanism is running at high speed, the roll 106 is out of the notch 105 and bears against the cam lever 104 at substantially the point 107. When the mechanism is running at low speed, the said roll 106 bears upon the 115 surface of the said cam lever 104 at substantially the point 108.

It will be understood from the foregoing that in the event of weft fault or failure, the mechanism, whether running at low speed 120 or at high speed, is stopped, and that the mechanism may be manually stopped or may be manually shifted to either high or low speed.

It will be understood that the invention in 125 certain aspects thereof is adapted to stop motion devices other than for textile machinery, and that the invention has a wide field of application in textile machinery of various types.

Having thus described one illustrative embodiment of my invention, I desire it to be understood that although specific terms are employed, they are used in a generic and descriptive sense and not for purposes of limitation, the scope of the invention being set forth in the following claims.

Claims—

1. Textile mechanism comprising in combination, a clutch having three positions, namely, a high speed position, a low speed position and a neutral position, driving members adapted to be actuated by said clutch when in its high speed position or 10 low speed position respectively, so as to drive the mechanism at said respective speeds, means to supply yarn or thread, a detector for said yarn or thread, and means caused to function by said detector through predetermined defective condition of the 15 yarn or thread, thereby to move the clutch into said neutral position.

2. Textile mechanism comprising in combination, a shaft having a high speed gear and a low speed gear thereon, and a clutch adapted effectively to drive either of said gears or to be moved to a neutral position, means to supply yarn or thread, a detector for said yarn or thread, and means caused 20 to function by said detector through predetermined defective condition of the 25 yarn or thread, thereby to move the clutch into said neutral position.

3. Textile mechanism comprising in combination, gears to drive the mechanism at high speed and at low speed respectively, a clutch adapted to render either of said gears effective or to be moved to a neutral position, manual means to move said clutch into 30 any one of said three positions, means to supply yarn or thread, a detector for said 35 yarn or thread, and means caused to function by said detector through predetermined defective condition of the 40 yarn or thread, thereby to move the clutch into said neutral position.

4. Textile mechanism comprising in combination, gears to drive the mechanism at high speed and at low speed respectively, a 50 lever 83 having three positions, a clutch, connections from said lever to said clutch to move the clutch into effective driving relation with said high speed gear or said low speed gear or into a neutral position, means 55 to supply yarn or thread, a detector for said yarn or thread, and means caused to function by said detector through predetermined defective condition of said 60 yarn or thread to move the clutch from either high speed or low speed position into neutral position.

5. Textile mechanism comprising in combination, gears to drive the mechanism at high speed and at low speed respectively, a clutch adapted to be moved to cause the 65 functioning of either the high speed gear or

the low speed gear or to be moved into an intermediate neutral position, means to supply yarn or thread, a detector for said yarn or thread, and means caused to function by said detector through predetermined defective condition of said yarn or thread to move the clutch from either high speed or low speed position into neutral position.

6. Stop mechanism comprising in combination, a member mounted for to and fro movement, means moved by movement of said member to stop the mechanism of which said member is a part, a second member co-operating with the first member and having a formation adapted to be engaged by either 70 one of two formations upon the first member, and whereby the running of the mechanism at two different speeds is controlled, and means governed by predetermined defective condition in the material acted on by 75 the mechanism to move said second mentioned member so as to permit the first mentioned member to occupy an intermediate position out of contact with the said formations, whereby the mechanism is stopped.

7. Textile mechanism having means either to drive the same at high speed or at low speed, means to supply a thread or yarn, and means to stop the machine upon predetermined defective condition of said yarn or 80 thread from either high speed or low speed, said means including a member mounted for to and fro movement, means adapted to be moved thereby to effect the driving of the mechanism at high speed or low speed or to 85 stop the same, a second member having a formation to engage spaced portions of the first member, and means controlled by the 90 yarn or thread to move said formation upon the second member out of engagement with the first member for the purpose set forth.

8. Textile mechanism having means either to drive the same at high speed or at low speed, means to supply a thread or yarn, and means to stop the machine upon predetermined defective condition of said yarn or 100 thread from either high speed or low speed, said means including a member mounted for 105 rocking movement, means moved by said member to effect driving of the machine at high speed or low speed or stop the same, a second member having a formation to engage spaced portions of the first member, and means controlled by the presence or absence of a yarn or thread to govern the position of the second member.

9. Textile mechanism having means either to drive the same at high speed or at low speed, means to supply a thread or yarn, and means to stop the machine upon predetermined defective condition of said yarn or 110 thread from either high speed or low speed, said means including a member 54 mounted for rocking movement and having shoulders 115 55, 56, means moved by said member 54 to 120 125 130

determine the running of the machine at high speed or low speed, or the stoppage thereof, a second member 43 having a formation 44, a feeler for the yarn or thread, 5 and intermediate connections between said feeler and said second member 43.

10. Textile mechanism having means either to drive the same at high speed or at low speed, means to supply a thread or yarn, 10 and means to stop the machine upon predetermined defective condition of said yarn or thread from either high speed or low speed, said means including a member 54 mounted for rocking movement, a member 63 moved 15 by movement of the member 54, a pivoted member 41, 43 having a formation 44 to be engaged by spaced portions of the member 54, a feeler for the yarn or thread, and a connection including the member 31 between 20 said feeler and said member 43.

11. Textile mechanism having means either to drive the same at high speed or at low speed, means to supply a thread or yarn, and means to stop the machine upon predetermined defective condition of said yarn or 25 thread from either high speed or low speed, said means including a member 54 mounted for rocking movement, means operatively connected with said member and adapted to 30 be moved thereby to control the high speed or the low speed or the stopping position of the mechanism, a member 43 having a formation to engage spaced portions of the member 54, a feeler for the yarn or thread, 35 reciprocal means to move said feeler, and means moved by said reciprocal movement to change the position of said member 43.

12. Textile mechanism having means either 40 to drive the same at high speed or at low speed, means to supply a thread or yarn, and means to stop the machine upon predetermined defective condition of said yarn or thread from either high speed or low speed, 45 said means including a member 54 adapted to determine whether the machine shall run at high speed or at low speed or be stationary, a movable member 43 having a formation to engage spaced portions of the member 54, a feeler, a rod 31 to move the same, means tending normally to reciprocate the rod 31, and means caused to move by an interruption in the movement of the member 31 to change the position of the member 43 50 with respect to the member 54.

13. Textile mechanism having means either to drive the same at high speed or at low speed, means to supply a thread or yarn, and means to stop the machine upon predetermined defective condition of said yarn or 60 thread from either high speed or low speed, said means including a member 54 to place the mechanism in either high speed or in low speed or in stopping position, a member 43 having a formation to engage spaced por-

tions of the member 54, means governed by the presence or absence of yarn or thread to govern the relation of the member 43 with respect to the member 54 and manual means to shift said member 54.

70

14. Textile mechanism having means either to drive the same at high speed or at low speed, means to supply a thread or yarn, and means to stop the machine upon predetermined defective condition of said yarn or 75 thread from either high speed or low speed, said means including a member 54 to determine the position of the mechanism for high speed, for low speed or for stopping, a lever 53 having a formation to engage spaced portions of the member 54, a feeler for the thread or yarn, operative connections between said feeler and a lever 53 to control the position of the latter.

80

15. Textile mechanism having means either 85 to drive the same at high speed or at low speed, means to supply a thread or yarn, and means to stop the machine upon predetermined defective condition of said yarn or thread from either high speed or low speed, 90 said means including a member 54 to determine the position of the mechanism for high speed, for low speed or for stopping, a lever 53 having a formation to engage spaced portions of the member 54, a feeler for the 95 thread or yarn, operative connections between said feeler and a lever 53 to control the position of the latter, and manual means operatively connected to the member 54 to move it into position for high speed, for low 100 speed or for stopping the mechanism.

16. Textile mechanism having means either to drive the same at high speed or at low speed, means to supply a thread or yarn, and means to stop the machine upon predetermined defective condition of said yarn or thread from either high speed or low speed, 105 said means including a member 54, means movable thereby to determine the high speed, low speed or stopping position of the mechanism, a lever 43 having a formation to engage spaced portions of the member 54, a feeler for the yarn or thread, a member to reciprocate said feeler but adapted to be held from reciprocation upon the absence of 110 yarn or thread, and lever means adapted to be moved by interruption of the reciprocating movement of said reciprocating member to change the position of the lever 53 with respect to the member 54.

115

17. Textile mechanism having means either to drive the same at high speed or at low speed, means to supply a thread or yarn, and means to stop the machine upon predetermined defective condition of said yarn or 125 thread from either high speed or low speed, said means including a feeler for the yarn or thread, a rod 31 to move the feeler, means tending normally to reciprocate the rod 31 and including a lever 22, 24, lever means 130

carried by the lever 22, 24, and adapted to be shifted in position upon interruption of movement of the rod 31, a lever 41, 43 governed in position by the said lever means, 5 and a member 54 adapted to engage the lever 41, 43, and means adapted to be moved by said member 54 to change the direction of the mechanism.

18. Textile mechanism comprising in combination gears respectively to drive the mechanism at high speed and at low speed, a clutch, means to move the same into effective driving relation to the high speed gear or to the low speed gear or into a neutral position, 15 a brake, connections to apply the brake when the clutch is in neutral position, means to supply yarn or thread, a detector for said yarn or thread, and means caused to function by said detector through predetermined defective condition of said yarn or thread to move the clutch from either high speed or low speed position into neutral position.

19. Textile mechanism comprising in combination, means to drive the mechanism at high speed and at low speed respectively, a clutch adapted to cause the functioning of either the high speed gear or the low speed gear or to be moved into a neutral position, a brake, means for automatically applying 30 the brake when the clutch is in neutral position, means to supply yarn or thread, a detector for said yarn or thread, and means caused to function by said detector through predetermined defective condition of said 35 yarn or thread to move the clutch from

either high speed or low speed position into neutral position.

20. Textile mechanism comprising in combination, gears to drive the mechanism at high speed and at low speed respectively, a shaft having two positions, means to move said shaft into one of said positions to cause the high speed gear to function and to move it into the other position to cause the low speed gear to function, means to supply 45 yarn or thread, a detector for said yarn or thread, and means caused to function by said detector through predetermined defective condition of the yarn or thread whether the high speed gear or the low speed gear be 50 functioning.

21. Textile mechanism comprising in combination, gears to drive the mechanism at high speed and at low speed respectively, a member having three positions, means to move said member into one position to cause the high speed gear to function, into another position to cause the low speed gear to function, and to a third position to cause the textile mechanism to come to rest, means to supply yarn or thread, a detector for said yarn or thread, and means caused to function by said detector through predetermined defective condition of said yarn or thread to stop the mechanism whether the high speed 65 gear or the low speed gear be functioning.

In testimony whereof, I have signed my name to this specification.

EDGAR F. HATHAWAY.
